UNITED STATES PATENT OFFICE.

FRANK ROBERT McBERTY, OF ANTWERP, BELGIUM, ASSIGNOR TO WESTERN ELECTRIC COMPANY, OF NEW YORK, N. Y., A CORPORATION OF ILLINOIS.

TELEPHONE-EXCHANGE SYSTEM.

1,123,340.

Specification of Letters Patent.

Patented Jan. 5, 1915.

Application filed August 21, 1913. Serial No. 785,870.

To all whom it may concern:

Be it known that I, FRANK ROBERT McBERTY, a citizen of the United States, residing at 49 Boulevard Leopold, Antwerp, Belgium, have invented certain new and useful Improvements in Telephone-Exchange Systems, of which the following is a full, clear, concise, and exact description.

This invention relates to telephone exchange systems and has to do more particularly with a test or controlling circuit for telephone exchange systems utilizing automatic switches to extend the desired connection.

15 In automatic switches of the character referred to there is usually a circuit known as the "test circuit" thereof including a test brush on the movable portion of such switch which tests on the one hand the calling or 20 non-calling condition of the line, or, on the other hand, the busy or idle condition of the line, depending upon whether such automatic switch is a line finder switch, a trunk finder switch or a selector. The invention 25 herein described has particularly to do with an improved system and arrangement involving such a test circuit.

In British Patent No. 21,260/11 is shown a line finder of the character referred to, and 30 in British Patent No. 21,259/11 is shown a trunk finder switch and a selector of the character referred to. While the invention is disclosed and described herein with specific reference to switches of the character 35 referred to, it will, of course, be understood it is not limited to switches of these specific types, nor to any specific types of switches, but is readily applicable, as will be understood by those skilled in the art, to switches 40 and systems widely varying in type and character.

One of the features of the invention is a test circuit in which two test relays associated with the test circuit, performing interacting but independent functions, are included in such circuit in parallel whereby a more sensitive and accurate operation of such relays is accomplished.

Another feature of the invention relates 50 particularly to automatic switches which are power driven and in which a test guard is placed upon the line selected immediately that the brushes of the switch come in contact with the terminals of such line, although the motion of the switch is not ar-

rested until such brushes are properly centered upon such terminals. This feature involves an arrangement of the circuit of the power-control test relay by which the power for driving the brush carriage of the 60 switch is maintained and cut off at the proper time, in such a manner that this relay operates to cut off such power by the closure of the circuit therethrough rather than by the removal of a shunt from around 65 such relay.

A still further feature of the invention pertains to the reduction of current fluctuations in the test circuit of the selector switches of the character above referred to. 70

Further novel and improved features of the invention will sufficiently appear in the detailed description hereinafter set forth.

In the drawings:—Figures 1 and 1^a show the invention as applied to a line finder switch of the type set forth in British Patent 21,260/11; Fig. 2 is a diagrammatic detail of a portion of the apparatus and circuits of Fig. 1; and Fig. 3 shows the invention as applied to a selector switch of the 80 type shown in British Patent No. 21,259/11.

The structure of the switches themselves and of the sequence switches shown as a part of the diagrams herein will sufficiently appear from an examination of the British 85 patents referred to and British Patents No. 20,840—09 and No. 16,867—11, and 20,841—09.

The arrangement and operation of the test circuit involving the invention will best 90 appear in the description of the operation of the respective switches with which it is shown herein associated.

Referring first to Figs. 1 and 1^a—when the subscriber at sub-station 50 removes his receiver from its hook, line relay 51 is energized, placing a selectable potential upon all the multiple test terminals 68 of the multiple sets of terminals 65, 66, 67, 68, individual to this subscriber's line in all the line 100 finder switches serving the group to which this line belongs, and the pilot relay 52, energized by the attraction of the line relay armature, starts in motion all such line finder switches which are idle. These line 105 finder switches differ from those shown in British Patent No. 21,260/11 only in the arrangement of the interrupter devices 39, 70, shown at the top thereof. In the switch herein shown the interrupter device is so ar- 110

ranged that the lever 69 will rest upon a tooth of the interrupter plate 70 only when the brushes 71, 72, 73, 74 are properly centered upon the terminals 65, 66, 67, 68 corresponding to such tooth upon plate 70. At all times when the brushes 71, 72, 73, 74 are passing from one set of terminals to the next the lever 69 will be passing between teeth on the interrupter plate 70 and out of contact therewith. This is clearly shown in the drawings and especially so in Fig. 2 thereof.

In the movement of the line finder switch 75, the test brush 74 as it passes over the test terminals 68 of non-calling lines, will find no or insufficient potential existing thereon and no connections of the line finder apparatus will take place. As soon, however, as the test brush 74 comes in contact with the terminal 68 of a calling line on which there exists selectable potential a circuit will be established, including with the battery, the pilot relay 52, the armature and front contact of the line relay 51, resistance 53, terminal 68, brush 74, sequence switch contact 59 bottom, upper high resistance winding of the test relay 76, sequence switch contact 60 to ground and back to battery. If at this time the test brush 74 of no other line finder rests upon the terminal 68 of this calling line, sufficient current will pass through the upper winding of the relay 76 to energize this relay, which will thereupon attract its armature and immediately close a low resistance circuit from the brush 74 to ground through its lower low resistance winding, which circuit while maintaining relay 76 energized will so reduce the potential upon the test terminal 68 that the corresponding relay 76 of another switch whose test brush 74 comes in contact with the terminal 68 of this line will not receive sufficient current for its energization and consequently the switch will continue in motion. At this time, however, the movement of the brush carriage of the line finder 75 will not be immediately arrested but will continue until the lever 69 of the interrupter device comes in contact with a tooth on the plate 70 which tooth corresponds to the desired set of terminals. At this time a circuit will be established for the relay 77 in parallel with the low resistance winding of the relay 76, such circuit including the armature of such relay 76, contact 57 bottom, relay 77, contact 58 bottom, interrupter lever 69, interrupter plate 70 to ground. This causes the immediate energization of the relay 77 and its armature thereupon opens the circuit of the power magnet 80 of the brush carriage and closes the circuit of the holding magnet 81 thereby causing the brush carriage to be positively stopped with the brushes in proper position over the line terminals; this relay also closes a circuit for the sequence switch 79, driving it out of its first and into its fourth position.

The subsequent operations of the apparatus associated with this line finder switch will now take place as described in the British Patent No. 21,260 referred to. It will be noted, however, that in the operation just described the operation of the power-control test relay 77 is produced by the closure of the battery circuit therethrough, and therefore responds quickly rather than more sluggishly as in a circuit wherein the operation of this relay takes place by the removal of a shunt therearound. Furthermore, it will be observed that the current fluctuations in the test circuit herein disclosed are much less than in the test circuit of the character referred to. This will be apparent when it is considered that in such test circuits sufficient current must flow from the shunt to ground through the interrupter device to energize the relay similar to relay 77 when the shunt is removed. Therefore, when the test brush first comes in contact with the test terminal and the double wound test relay 76 is energized, considerable current will flow from the low resistance winding thereof to ground, whereas when the brushes are properly centered and the shunt is removed there being a greater resistance in the test circuit, less current flows therein although the resistance must be sufficiently low to allow sufficient current to pass to energize the relay 77 and to reduce the potential upon the multiple test terminals to such a point that no other line finder may seize the line to which such test terminal is individual.

According to the circuit of the present invention, the windings of the test relays 76 and 77 will be of considerably less resistance than the corresponding relays in test circuits of the character referred to, while maintaining the proper margins and accurateness of operation. By this means and by the multiple arrangement instead of the series arrangement of the test relays 76 and 77, undesirable fluctuations of current will not take place in the test circuit.

Referring now more specifically to Fig. 3 it will be observed that in the eighth position of the sequence switch 303 the group selector 300 is searching and testing for an idle trunk line in the selected group. As the test brush 303 moves over the terminals 303 of busy lines it will find insufficient potential thereon to cause the energization of the relay 93 by means of its high resistance left hand winding. When, however, the test brush 303 reaches the test terminal of an idle line upon which exists unshunted potential, sufficient current will pass through the high resistance winding of the relay 93 to cause it to be energized, thereby attracting its armature which will establish a parallel path through its low resistance right hand winding, so reducing the potential on the multiple test

terminals 303 of the seized line that it will test busy to all other group selectors in which it appears. The interrupter lever 99 not as yet having come in contact with the 5 tooth of the interrupter plate 98 corresponding to the set of terminals 301, 302, 303, the relay 90 is not as yet energized and the brush carriage of the group selector continues in motion until the interrupter lever 10 comes into contact with the tooth of the interrupter plate and the circuit is closed therethrough to energize the relay 90 which responds and immediately stops the movement of the brush carriage by opening the 15 circuit of the power magnet 306 and closing the circuit of the holding magnet 308, which positively stops the brush carriage with its brushes 301^a, 302^a, 303^a properly positioned over the selected terminals 301, 302, and 20 303. At the same time a circuit is closed for the sequence switch 305, driving it out of its eighth position. Subsequent operations may take place as described in the British Patent No. 21,259 referred to.

25 Referring specifically to Fig. 2,—this view very clearly shows the relative arrangement of the contact brush 74 and the interrupter lever 69 to the contact terminal 68 and the corresponding tooth upon the 30 interrupter plate 70. This figure also shows diagrammatically the circuits associated with such parts. In this figure it will be seen that as soon as the test brush 74 comes in contact with the test terminal 68, the 35 test relay 76 is energized closing through its second winding a low resistance busy guard for the test terminal 68, and at the same time preparing a circuit for the power-control test relay 77 which circuit will be 40 closed a moment later when the lever 69 comes in contact with the tooth of the interrupter plate 70 corresponding to the terminals of the line seized; and the relay 77 will thereupon open the circuit of the driving 45 magnet 80 and close the circuit of the holding magnet 81, which arrests the movement of the switch with the brushes properly centered over the desired terminals.

Having now particularly described and 50 ascertained the nature of the said invention and in what manner the same is to be performed, I declare that what I claim is:—

1. In a telephone exchange system, the combination with a plurality of lines, of automatic switches for interconnecting the same, a circuit associated with each of said switches adapted to test said lines and including two relays in parallel adapted to respond if the line tested is idle, and means 55 controlled by one relay to render the multiple terminals of such line busy and means controlled by the other to arrest the movement of the switch.

2. In a telephone exchange system, the 60 combination with a plurality of lines, of au-

tomatic selectors adapted to interconnect the same, a circuit associated with each of said selectors adapted to test said lines and including two relays, one responding immediately if the line is idle to render busy its 70 multiple terminals and preparing a circuit in parallel with itself for the other relay which controls the stopping of the selector, and a switch carried by the selector for closing said circuit to stop the same when the selector is properly positioned.

3. In a telephone exchange system, the combination with a plurality of lines, of automatic selectors adapted to interconnect the same, a constantly rotating shaft adapted to be coupled to said selectors to drive the same, a circuit associated with each of said selectors, adapted to test said lines and including two relays in parallel adapted to respond if the line tested is idle, one to render its multiple terminals busy and the other to uncouple the selector from the power shaft.

4. In a telephone exchange system, the combination with a plurality of lines, of automatic selectors adapted to interconnect the same, a constantly rotating shaft adapted to be coupled to said selectors to drive the same, a circuit associated with each of said selectors adapted to test said lines and including two relays in parallel, one responding immediately if the line is idle to render busy its multiple terminals and preparing a circuit in parallel with itself for the other relay which controls the coupling of the selector to the shaft, and a switch carried by the selector for closing said circuit to stop the same when the selector is properly positioned.

5. In a telephone system, the combination with a plurality of lines, of automatic selectors adapted to interconnect the same, a power shaft for driving said selectors, a battery, multiple test contacts for said lines on said selectors having normally applied thereto the full potential of said battery, a circuit associated with each of said selectors adapted to test said lines and including two relays, one having a high resistance potential reducing winding, said relay responding by its high resistance winding if the line is idle to render said line busy by reducing the potential of its multiple test contacts by including its low resistance winding in circuit with said battery, and preparing a circuit for the other relay which controls the disconnection of the selector from the power shaft, and a switch carried by the selector adapted to close said circuit to stop the same when the selector is properly positioned.

6. In a telephone exchange system, the combination with a plurality of lines, of an automatic switch for interconnecting the same, a test circuit associated with said switch and including two devices in paral-

lel responsive to line conditions, means controlled by one device to establish a busy condition at the terminals of the line tested, and means controlled by the other device to govern the movement of the automatic switch.

In witness whereof, I hereunto subscribe my name this 24th day of July A. D., 1913.

FRANK ROBERT McBERTY.
